[57] CLAIM

The ornamental design for a garment hanger, as shown and described.

DESCRIPTION

FIG. 1 is a front, top perspective view of a garment hanger showing my new design;

FIG. 2 is a rear, bottom perspective view thereof;

FIG. 3 is a front view thereof;

FIG. 4 is a fragmentary top, perspective view thereof, with the clip in the open position for clarity of illustration;

FIG. 5 is a front, top perspective view of a second embodiment of the design of FIG. 1, the only difference between the showing of the rear in FIG. 2 being the inclusion of the cap on the hook;

FIG. 6 is a front view of FIG. 5;

FIG. 7 is a front, top perspective view of a third embodiment of the design of FIG. 1;

FIG. 8 is a rear, bottom perspective view of FIG. 7;

FIG. 9 is a front view of FIG. 7.

III. 3.

FIG. 8.
